UNITED STATES PATENT OFFICE.

THOMAS SCHUSTER, OF PHOENIX, ARIZONA.

MOLD FOR CONCRETE PIPES.

Application filed January 27, 1921, Serial No. 440,441. Renewed June 8, 1923.

To all whom it may concern:

Be it known that I, THOMAS SCHUSTER, a citizen of the United States, residing at Phoenix, in the county of Maricopa and 5 State of Arizona, have invented certain new and useful Improvements in Molds for Concrete Pipes; and I do declare the following to be a full, clear, and exact description of the invention, such as will enable others 10 skilled in the art to which it appertains to make and use the same.

This invention relates to improvements in molds for forming concrete pipes, and it has for one of its objects to generally improve 15 upon devices of this class by the provision of one of extreme simplicity and durability, which is of such construction that it may be easily and readily assembled for the filling operation, and can thereafter 20 be just as quickly and easily disassembled for removal of the hardened casting, the time saved by the employment of such a mold insuring an increased output of pipe-lengths.

Another object of the invention is to provide a mold of the above mentioned type made up of an outer casing and an inner core member, each of which are expandable and are retained in proper spaced relation 25 by rings arranged, one at the bottom and one at the top between the casing and the core, the inner faces of these rings being especially shaped to give a corresponding shape to the ends of the pipe-lengths so that 30 when the complete lengths are joined in forming a pipe-line, tight connection between these various lengths is insured.

A further object of the invention is to provide a mold embodying the aforesaid 40 outer casing and core member, the bottom of the latter being in the form of a novel expander which is such that it will retain the core in a true concentric shape and prevent it from becoming crushed by the surrounding concrete.

A still further object of the invention is to provide a mold embodying the aforesaid novel expandable bottom for the core together with a special wedge for expanding 45 the segments of which the bottom is composed and a special tool for removing the wedge.

Still another object of the invention is to provide a mold embodying a hopper at 50 its upper end and a removable cover for the core with coacting means between the

cover and hopper for preventing accidental displacement of the cover.

Another object and feature of the invention is to provide a mold wherein the core 60 is made from a sheet of metal rolled into tubular form with its ends overlapping each other, this member being reinforced by an internal rib and being provided with internal brackets to permit the use of a special tool for contracting the core to permit 65 easy and ready removal of the latter from the casting.

These and other objects and advantages 70 of the invention will become apparent during the course of the following description.

In the accompanying drawings forming a part of this specification and in which like numerals are employed to designate like 75 parts throughout the same:

Figure 1 is a vertical sectional view of a mold constructed in accordance with this invention.

Figure 2 is a sectional view of the upper portion of the mold showing a hopper and 80 other adjacent parts removed and the upper spacing ring in place.

Figure 3 is a similar view of the lower portion of the mold taken at substantially right angles to Fig. 1, the special core contracting tool being shown in position for 85 use.

Figures 4 and 5 are horizontal sections taken on the planes of the lines 4-4 and 90 5-5 respectively of Fig. 3.

Figure 6 is a detail perspective view of a portion of the shaping ring which surrounds the exterior upper end of the core member.

Figure 7 is a detail view of one of the retaining rings which are placed inside the 95 core member at the top of the latter.

Figure 8 is a detail perspective view showing the manner in which the overlapped ends of the outer casing are connected.

Figures 9, 10 and 11 are perspective views 100 of a wedge, wedge remover and core contracting tool which I employ in connection with my mold.

Figure 12 is a top plan view, with portions broken away, of a slightly modified 105 form of hopper embodying a shaping ring.

Figure 13 is a central sectional view taken therethrough on the plane of the line 13-13 of Fig. 12.

Figure 14 is a sectional view of the upper 110 portion of the mold showing the same equipped with a flange forming ring.

Figure 15 is a central vertical section through a slightly modified form of core embodying a different type of expander means.

5 Referring to the drawings, wherein the preferred embodiment of the invention is clearly illustrated, it will be seen that the improved mold comprises an outer cylindrical sheet metal casing 1 having its ends overlapped and secured together as disclosed in Fig. 8. By reference to this figure, it will be seen that the casing is formed on one of its edges with a plurality of slots 2 which receive screw-threaded studs 3 carried by the 10 other end of the sheet, binding nuts 4, preferably wing-nuts, serving to bind the overlapped ends of the sheet together in the manner disclosed. This is one way in which the ends of the casing may be secured together 15 but I do not desire to be limited to this particular construction since any other suitable means may be well employed for the purpose. Arranged in the casing and spaced therefrom to provide the necessary space for 20 pouring the liquid concrete, is a core member 5 which is likewise formed from a sheet of material rolled and having its ends overlapped. For the purpose of providing the proper space between the casing and core 25 for forming a pipe-length of a predetermined thickness, also for assisting in retaining the parts 1 and 5 in true concentric shape, I make use of upper and lower spacing rings 6 and 7 respectively. At this 30 point, I wish to direct attention to the fact that the inner faces of these rings are especially shaped to give corresponding shapes to the ends of the pipe-lengths so that when the completed lengths are aligned to form 35 a pipe-line, tight connection between the various lengths will be insured. I have shown the rings as formed with a particular bead. However, they may be shaped otherwise if desired or necessary. Also, I wish to have 40 it understood that the upper ring 7 is not placed in position until after the filling operation has been completed and the hopper and adjacent parts removed.

45 As before intimated, I make use of a novel expander for the core which also serves the additional function of forming the bottom of said core. While this expander may be of some other construction, I prefer to construct it as better shown 50 in Figs. 4 and 5. By reference to these figures, it will be seen that the expander is made up of a pair of spaced substantially triangular blocks 8 which have their inner adjacent edges bevelled as indicated at 55 9 for a purpose to be hereinafter described. Abutting the outer edges of the blocks 8 and spaced from one another, are a plurality of segments 10 having straight inner edges for engagement with the blocks 8 and curved 60 outer edges for contact with the inner wall 65

of the core 5. The blocks and segments are moved inwardly to decrease the diameter of the expander automatically by the contraction of the core. On the other hand, they are expanded by the employment of a wedge 11 which is positioned between the blocks 8 to coact with the bevelled edges 9. At this point, I may mention that the blocks and segments may, if desired, be composed of wood to reduce the cost of manufacture as 70 much as possible. To prevent relative displacement of the various members of the expander and to serve as a protector therefor, I employ a pair of circular plates 12 and 13 respectively, the first named plate being positioned on top of the blocks and segments and the remaining plate being disposed beneath these parts as shown in Figs. 1 and 3. In order to connect the plates together and in turn retain the parts of the 75 expander in their proper relative positions, the lower plate 13 is provided with upwardly extending studs 14 which pass through notches 15 formed in the segments 10 and in turn through apertures formed in the upper plate 12, nuts 16 being connected to the free projecting ends of the bolts 14. With this construction and arrangement, it will be seen that the desired relative movement of the parts of the expander may be obtained, and yet the parts may be easily and readily separated for replacement of the parts if found necessary. It is, of course, understood that the upper plate 12 is formed 80 with a central slot for passage of the wedge. It may be well to state that the wedge in its preferred form includes a lateral headed extension 17 which construction permits use of a special wedge removing tool 18 as shown in Fig. 10. This tool in accordance with my 85 ideas includes a shank 19 having at one end a handle 20 and at its opposite end a head 21 provided with specially constructed fingers 22 for engagement with the head of the wedge. In placing the tool on the head 90 of the wedge, it is only necessary to permit said head to pass between the spaced fingers, after which the tool will be slightly rotated so that the lateral ends of the fingers will become engaged with the head. When 95 the tool is thus connected to the wedge, the latter may be easily and readily removed which is sometimes not the case with the ordinary construction. I deem it advisable to mention at this point, that although I have shown and described a particular kind of wedge and wedge removing tool, I do not 100 wish to be limited to the particular construction of the members shown, since any other suitable construction may well serve 105 the same purpose.

110 By referring now to the upper end of the mold, it will be seen that I preferably close the upper open end of the core 5 by means of a cover 23, this cover being allowed to 115

remain in position until after the concrete is poured between the casing and the core. It is to be noted that the cover includes a comparatively wide cylindrical rim 24 which is designed to extend down into the core to assist in retaining this end of the latter in true concentric shape. By preference, the lower end of the rim 24 is directed inwardly as indicated at 25 to increase the 5 rigidity of this rim. It may also be advisable to employ one or more retaining rings 26 for disposition in the core at the position indicated, these rings assisting in retaining the core in proper shape and preventing the 10 possibility of the same becoming crushed. This retaining ring 26 is preferably constructed as shown in Fig. 7, that is, it is provided with a reinforcing strip 27 which decidedly increases the strength of the ring. 15 To also assist in properly shaping this end of the core and to prevent possible expansion of the latter, I make use of a shaping ring 28 which surrounds the exterior of the core at the upper end of the latter. In its preferred form, this ring 28 is constructed as 20 better shown in Fig. 6 wherein it is disclosed that it is split and the ends directed laterally as shown at 29, one of these laterally directed ends carrying a suitable latch 25 30 for connecting the ends together when the ring is in operative position. With this construction, it will be seen that when the latch is removed to ineffective position, the resiliency of the ring will cause the ends to 35 automatically separate, thus permitting easy and ready removal of the ring from the core.

To assist in the filling operation, I make use of a flared hopper 31 which includes a 40 cylindrical neck 32 adapted to extend down into the outer casing 1 as shown in Fig. 1. I have already intimated that I provide 45 coacting means between the hopper and the aforesaid cover to prevent possible displacement of the latter. To this end and by reference to Fig. 1, it will be seen that the cover is provided with a central upstanding 50 projection 33 and that the hopper carries a pivoted bowed arm 34 which is centrally apertured to permit passage of the aforesaid projection 33 therethrough.

It sometimes happens that difficulty is experienced in contracting the core and to overcome this, I make use of a special tool 55 35 for accomplishing this end. The tool is better shown in Fig. 11 and by reference to this figure, it will be seen that it comprises a handle equipped with a pair of pivoted hooks 36, the laterally bent free ends of which 60 are adapted to be inserted in apertures in the brackets 37 arranged on the interior of the core slightly above the lower end of the latter. In Fig. 3 I have shown the tool in position for use and it is obvious that by 65 grasping the handle and giving it a turn in

the direction of the arrow, the contraction of the core will be easily accomplished. If desired, there may also be arranged on the interior of the core, a reinforcing rib 38 which will be preferably disposed adjacent 70 one of the ends of the core and will be disposed in a vertical position.

In Figs. 12 and 13 there is shown a slightly modified form of the invention wherein an examination will disclose that 75 the hopper 31^a has associated with it, a shaping ring 28^a, the two parts being secured together by suitable connectors 29^a. By combining the shaping ring with a hopper, the mold may be more easily and readily assembled as is obvious and the rigidity of 80 the shaping ring will be increased.

In some cases, it may be desired to equip the pipe-lengths with lateral connecting flanges instead of equipping them with the 85 special beads as formed by the novel spacing rings 6 and 7. In order to permit this, I make use of a quick detachable flange forming ring 39 for connection to the outer casing 1, this construction and arrangement of 90 parts being shown in Fig. 14.

The construction of expander already described is especially designed to be used in cases where relatively large and long lengths of pipe are being formed. However, the 95 same result may be accomplished in cases where smaller lengths of pipes are desired to be formed, by the construction and arrangement of core disclosed in the modified form of the invention in Fig. 15. Reference being had to this figure, it will be 100 seen that the core is provided on its inner wall adjacent one end and opposite the reinforcing rib 38 with a pair of inclined short 105 angle pieces 40 and when the ends of the core are overlapped and the pieces 40 brought close to the reinforcing rib 38, substantially V-shaped spaces are provided between these parts, and in these spaces, I 110 contemplate inserting wedges 41, which when driven toward one another, will cause the core to become expanded.

The method of using the mold is as follows: The core 5 is placed within the lower spacing ring 6 and the expander is then 115 placed inside of the core in the manner shown. The outer casing 1 is placed around the ring 6 and its ends overlapped and bound together by means of the wing-nuts 4. The shaping and retaining ring 28 is 120 then placed around the outside of the core at the top and the ends hooked together by means of the latch 30. Assuming that the expander has been placed in position at the bottom of the core and that the hopper and cover placed in the position shown in Fig. 1, the liquid concrete is poured between the casing and core and after this, the hopper and cover are removed and the upper spacing ring 7 is placed in position as indicated 125 130

in Fig. 2. If it is desired to expand the lower end of the core slightly, this may be done by forcing downwardly on the wedge. After the concrete becomes hardened, the expander and wedge are removed. Then the contracting tool 35 is brought into play for the purpose of contracting the core and withdrawing it from the completed casting. By loosening the nuts 4, the outer casing 10 can be easily removed and the mold set up again for forming another length of pipe. A careful consideration of the foregoing description taken in connection with the accompanying drawings is thought to be sufficient to enable persons skilled in the art to which the invention relates to obtain a clear understanding of the same. Therefore, a more lengthy description is deemed unnecessary.

20 Since probably the best results may be obtained with the construction and arrangement shown and described, this construction and arrangement is taken as a preferred embodiment of the invention. However, I wish it to be understood that minor changes within the scope of the invention may be resorted to.

I claim:

1. A mold for concrete pipes comprising an outer cylindrical casing, an inner expandible and contractible core arranged in and spaced from said casing, means for retaining the casing and core in spaced relation, means for holding the core in true concentric shape, and an expandible bottom for the latter including a pair of triangular blocks having bevelled edges disposed in spaced relation, and a plurality of other blocks or segments engaging and arranged about the first named blocks and forming a substantial disk, the aforesaid bevels serving to permit use of a wedge for increasing the diameter of the disk and in turn expanding said core.
2. A mold for concrete pipes including an expanding device composed of a pair of

triangular blocks having bevelled edges disposed in spaced relation, and a plurality of other blocks or segments engaging and arranged about the first named blocks and forming a disk, the aforesaid bevels serving to permit use of a wedge for increasing the diameter of the disk so as to enable the core with which it co-acts to be expanded.

3. The structure set for in claim 1 together with a pair of plates, arranged one on top of the blocks and one beneath them, and means connecting the plates together.

4. A mold for concrete pipes comprising inner and outer cylindrical casings, a cover for the inner casing provided with a depending neck extending into the upper end of the latter, being provided with an upstanding projection, a hopper having its lower end extended into the outer casing, and a centrally apertured pivotally mounted cross-arm extending over the upper edge of the hopper, said projection extending removably through the aperture in this arm to assist in preventing displacement of the cover.

5. A mold for pipes comprising a cylindrical outer casing, a cylindrical core arranged therein and spaced therefrom, a hopper telescoping into the upper end of the casing, carrying a shaping ring at its lower end into which the upper end of the core extends; and means inside of the core for forcing it into tight engagement with said ring.

6. In combination a wedge provided with a headed lateral extension, and a removing tool including a headed shank provided with spaced fingers to engage the head on said extension for removing said wedge.

In testimony whereof I have hereunto set my hand in the presence of two subscribing witnesses.

THOMAS SCHUSTER.
